UNITED STATES PATENT OFFICE.

JAMES SMITH, OF EALING, ENGLAND, ASSIGNOR TO BABCOCK & WILCOX COMPANY,
OF BAYONNE, NEW JERSEY, A CORPORATION OF NEW JERSEY.

APPARATUS FOR CHARGING OPEN-HEARTH FURNACES AND THE LIKE.

1,028,620.

Specification of Letters Patent.

Patented June 4, 1912.

Application filed January 18, 1912. Serial No. 671,070.

To all whom it may concern:

Be it known that I, JAMES SMITH, a subject of the King of Great Britain, residing at Ealing, in the county of Middlesex, England, have invented certain new and useful Improvements in Apparatus for Charging Open-Hearth Furnaces and the Like, of which the following is a specification.

This invention relates to an apparatus for charging open-hearth or similar furnaces, and is an improvement upon or modification of that described in a companion application executed and filed of even date herewith. In the apparatus described in said companion application the tiltable charging arm or bar, which is mounted on a platform or carriage rotatable on a vertical axis, is adapted to be rotated or oscillated on a longitudinal axis intersecting said vertical axis. According to the present improvement or modification, the charging arm or bar is disposed at one side of the vertical axis of said rotatable carriage so as to permit a central column carrying collector gear for the electric motors, which impart the respective motions to the apparatus, to be extended above the charging arm and thus afford ready access to the collector gear and the electric connections between the rotating and non-rotating portions of the machine, and also allow direct connection with preferably overhead electric conductors as hereinafter particularly described. In previous designs of similar charging machines the rotary collector gear has been fixed in a comparatively inaccessible position below the turn table; this is avoided by the present design.

In the accompanying drawings Figure 1 is an elevation of a charging apparatus of the kind referred to embodying the invention; Fig. 2 is a part plan; and Fig. 3 is a part elevation at right angles to Fig. 1.

Similar reference numerals indicate similar parts in the several views.

Referring to the drawings, the charging apparatus comprises a main traveling structure 1 made up of suitably braced I-beams or the like resting on wheels 2 adapted to be rotated through the intermediary of suitable gearing 4—5 from an electric motor 6, whereby the said structure may be traversed along stationary rails 7 disposed parallel to the furnace front.

Mounted to run on the structure 1 in a direction at right angles to the line of move-

ment of the structure, that is, toward or away from the furnace opening, is a carriage 8 to which are connected the ends of sprocket chains 9, said chains being led around sprocket wheels 10 and 11. The sprocket wheels 10 are fast on the shaft 12 mounted in bearings on the main structure 1, said shaft being rotated through gearing 13 driven from an electric motor 14, said gearing and motor being located to one side of and at the rear of the structure 1, so that the component parts thereof are readily accessible and out of the dangerous heat from the furnace. It will be understood that the motor 14 and gearing 13 will participate in the movement of the structure 1 and be stationary relatively to the carriage 8, the gearing, chain connections, etc., acting positively to traverse the carriage.

The charging arm 15 is supported within a hollow bearing 16 having journals fitted in brackets 17 mounted on a turn table 18, the latter being mounted on the carriage 8. The turn table 18 may be rotatably supported in any suitable manner, as by roller bearings described in my said companion application. On the turn table is mounted an electric motor 19 which drives a worm gearing 20 and a gear 21 (see Fig. 2), the latter meshing with a fixed internal gear 22 on the carriage.

In addition to the rotation of the charging arm 15, through the rotation of the turn table the said arm has an independent movement of rotation on its longitudinal axis through the following mechanism: The rearward extension of the bearing 16 supports a platform 23 on which is supported an electric motor 24 driving a suitable train of gears, the worm wheel 25 of which (see Fig. 1) is fast on the shaft of the charging arm. The charging arm is also capable of a tilting movement on a transverse horizontal axis. As above stated, the bearing 16 has journals fitted in brackets 17 and said bearing is tilted by means of a crank 26 secured to shaft 27 located beneath bearing 16. To said crank are connected arms 28 provided with rollers 29 engaging guides on the rear portions of the bearing 16. The crank shaft 27 is driven through gearing 30 from an electric motor 31, the gearing being kept as low as possible relatively to the charging arm at one side thereof so as to afford an uninterrupted view of the charg-

ing arm and the load carried thereby when the furnace is being charged. It will be understood that the devices for tilting the charging arm operate on the same from 5 below.

As will be observed, more particularly with reference to Fig. 3, the charging arm 15 is located at one side of the vertical axis 32 of the turn table 18, while clearance is 10 provided at 33 to permit the charging arm to be tilted on its transverse horizontal axis at 34. This arrangement affords a convenient means for permitting a non-rotating central column 35 connected to the carriage 15 8 and carrying a known type of collector gear for the electric motors above referred to, to be carried above the charging arm 15 and thus afford ready access to the collector gear and allow direct connection to over 20 head conductors 36.

The upper end of the collector column 35 may be inclosed by a casing 37 having a ball and socket or like connection at 38 jointed as by means of a swivel joint 39 with a 25 suitably supported trolley on which are preferably mounted spring held arms 40 carrying rollers for engagement with the conductors 36.

What I claim and desire to secure by Letters Patent of the United States, is:—

1. In an apparatus of the character de-

scribed, the combination of a main traveling structure, a carriage mounted thereon, a turn table supported on the carriage, a charging arm supported on said table at one 35 side of the vertical axis of said table, a central column also mounted on said table, electric collector gear carried by said column, said collector gear being extended above the charging arm.

2. In an apparatus of the character described, the combination of a main traveling structure, a carriage mounted thereon, a turn table mounted on said carriage, a charging arm supported on said table at 45 one side of the vertical axis thereof, electric motors mounted on said turn table and mechanism actuated by said motors for rotating the turn table and for rotating said charging arm and also for tilting said arm on its horizontal axis, a central column, and an electric collector gear carried by said column, said collector gear being extended above the charging arm.

In testimony whereof I have hereunto 55 signed my name in the presence of two subscribing witnesses.

JAMES SMITH.
